CLAIM

The ornamental design for a tissue care device, as shown and described.

DESCRIPTION

FIG. 1 is a front, first-end, and right-side perspective view of a tissue care device in accordance with our design; FIG. 2 is a rear, first-end, and left-side perspective view thereof;

FIG. 3 is an enlarged perspective view of region 3 of FIG. 2;

FIG. 4 is a front view thereof;

FIG. 5 is a rear view thereof;

FIG. 6 is a right-side view thereof;

FIG. 7 is a left-side view thereof;

FIG. 8 is a first-end view thereof; and,

FIG. 9 is a second-end view thereof.

The even length dash-dash broken lines are used to illustrate portions of the tissue care device that form no part of the claimed design. In FIGS. 2 and 3, the dot-dash broken lines represent the sectional designation that forms no part of the claim.
